UNITED STATES PATENT OFFICE.

JAMES K. TULLY, OF ST. LOUIS, MISSOURI, ASSIGNOR TO METALLIC INDUSTRIES INC., OF ST. LOUIS, MISSOURI, A CORPORATION OF DELAWARE.

DESIGN FOR A CHILD'S VELOCIPED.

60,071.

Specification for Design.

Patented Dec. 20, 1921.

Application filed February 3, 1921. Serial No. 442,291. Term of patent 14 years.

To all whom it may concern:

Be it known that I, JAMES K. TULLY, a citizen of the United States, residing in the city of St. Louis, State of Missouri, have invented a new, original, and ornamental Design for a Child's Velocipede, of which the following is a specification, reference being had to the accompanying drawing, forming part thereof.

In the drawing,

Figure 1 is a plan of the velocipede;
Fig. 2 is a side elevation;
Fig. 3 is a bottom plan of the velocipede;
Fig. 4 is a front elevation; and
Fig. 5 is a rear elevation.

I claim:

The ornamental design for a child's velocipede as shown.

JAMES K. TULLY.
